UNITED STATES PATENT OFFICE

162,428

TEXTILE FABRIC

Walter Mitschke, North Bergen, N. J., assignor to Classic Weaving Corporation, North Bergen,
N. J.

Application September 27, 1950, Serial No. 12,375

Term of patent 3½ years

(Cl. D92—1)

To all whom it may concern:

Be it known that I, Walter Mitschke, a citizen of the United States of America, residing in North Bergen, county of Hudson, and State of New Jersey, have invented a new, original, and ornamental Design for a Textile Fabric, of which the following is a specification, reference being had to the accompanying drawing, forming part thereof, wherein the figure on the drawing is a plan view of a textile fabric, showing my new design. The dot and dash lines on the drawing outline a design unit, which unit is repeated in regular succession as indicated by the extensions beyond the unit boundaries.

I claim:

The ornamental design for a textile fabric, substantially as shown and described.

WALTER MITSCHKE.
